ATTORNEY.

UNITED STATES PATENT OFFICE.

ALFREDO FAVALE, OF DETROIT, MICHIGAN.

ELECTRIC WATER HEATER.

Application filed December 8, 1926. Serial No. 153,259.

My invention relates to an electric water heating apparatus, and has for its object an improved organization of parts by means of which water for domestic and similar purposes may be heated electrically at an appreciable distance, if so desired, from the point of storage or other supply of the water, and made available for drawing off as desired. In this construction the water tubes 10 are made to function as the secondary circuit of a transformer, while the primary transformer is divided into a number of sections between which loops of the water coil are interposed. I thus avoid the interference with the proper heat radiation which would otherwise occur, due to the objectionable temperature raising of the primary, and make it possible to secure a large and adequate supply of heating water with a 20 minimum expenditure of current.

In the drawings:

Figure 1 is an elevational view, partly diagrammatic, showing the details of the heating coil elements in connection with abbreviated representations of several floors of a building through which the pipes may pass.

Figure 2 is a plan view, partly in section, taken along the line 2—2 of Figure 1 and 30 looking in the direction of the arrows there shown.

A and B represent the frame sections of a support, between which are insulatedly located the several elements of the water-heating construction. At C is shown a switch controlling the current from a suitable source of external power. D, E and F represent the high resistance wires connecting the switch with the binding posts G, H 35 and I respectively, by means of which current is carried to the heating device. Each one of these binding posts forms the top of a resistance structure, in which respectively are spacedly positioned a 40 plurality of transformer primary elements as G¹, G², and G³, and H¹, H², and H³, and I¹, I², and I³. Between these lie exposed portions of the several cores, as N, about which are wound in horizontal series loops 45 of the water-conducting pipes J, K, L, and M, the pipes J and K constituting the supply and return elements respectively of one series, while the pipes L and M function similarly as to the other series or water circuit, and all being connected with the tank 50 or supply source Z, positioned suitably above

the electric heating device. The supply and return portions of each pipe series J and K, and L and M, respectively are not appurtenant, as regards their coil portions, to any 60 one of the vertically arranged resistance structures, but on the contrary the intermediate portions of each, that is, the coils between the straight sections, as J and K, and L and M, respectively are formed into three 65 series, horizontally aligned, each of which encircles a corresponding exposed portion of the core of each of the resistance structures G, H and I; thus in Figure 2 the coil section R, S and T will be understood as appurtenant to and a part of the pipe circuit L and M, while if a similar section were taken through the corresponding lower series of convolutions about the resistance elements G and H and I, they would form a 75 similar connection between the pipes J and K.

These series of tubes or pipes which I thus make to serve as secondary transformer elements may be used to effect the desired 80 heating short-circuiting separately, each pair being connected by a plate or bridge of metal; in Figure 1 these are, for the sake of clearness, illustrated as at different heights, the plate P connecting the pipes J and K, 85 while the plate Q functions similarly as to the pipes L and M. However, if desired one plate, as Q, might be connected with all four pipes, though in the preferred arrangement shown I am enabled to vary the degree 90 of resultant heating by changes of one or both of the plates to a higher or lower position.

I thus make use of the tendency of the heated water to rise, and thus make way for 95 the gravity-induced downward flow of the cold water through each of the inlet pipes J and L. The coil sections, as R, S and T, not being positioned about the transformer primary in any case, and in fact spaced 100 from them, and in case of their slight displacement actually insulated as well by their washers M, the heat of their water is communicated to the several transformer primaries.

Since to a degree the influence of the water already heated extends up into the inlet pipe of either series, thus tending to slacken the speed of the flow through the coils and outlet sections K and M of each series, it is sometimes advisable to effect the 110 injection of a supplemental flow of cold

water into either or both of the coil series at a point relatively near where the heating is going on most actively. To accomplish this I provide an auxiliary feed pipe V, 5 which leads downwardly from the tank Q to connection with each of the pipe series, as at X and Y respectively. The inflow thus induced reaches the coil sections proper at the beginning of their point of actual 10 heating, and thus may be used to accelerate the result desired, the possible flow through the pipe V being controlled by a hand valve W.

What I claim is:

15 1. An electric water heating apparatus, having in combination with a plurality of spacedly positioned core elements, a plurality of spacedly arranged primary transformer elements appurtenant to each of said 20 core elements, an energizing current wire appurtenant to each of said cores and its group of primary transformer elements, a plurality of water coils each connected with a supply source and each engaging with its 25 central portion about exposed portions of each core element intermediate certain of its primary transformer elements, each being

adapted to serve as a secondary transformer element because of the contact of its coiled portions with said core elements, and a 30 valve-controlled supplemental supply pipe connected with each of said water coils adjacent that portion of each adjacent one of said core elements.

2. In an electric water heater, in combination with a plurality of water coils having their central portions plurally looped, a plurality of core members spacedly arranged in parallel relation, a series of primary transformer members arranged in spaced relation about each of said core members, the central portion of each of said water coils engaging about some portion of each one of said core members intermediate the location thereabout of said primary transformer 45 members, electrical circuit wires leading from an external source of power to each of said core members, and an auxiliary water supply pipe connected with each of said water coils adjacent their central core-engaging 50 portions.

In testimony whereof, I sign this specification.

ING. ALFREDO FAVALE.
